UNITED STATES PATENT OFFICE.

RICHARD KNIGHT, OF MIDDLETON, NEW YORK.

TARGET DEVICE.

1,280,763.

Specification of Letters Patent.

Patented Oct. 8, 1918.

Application filed June 28, 1918. Serial No. 242,389.

To all whom it may concern:

Be it known that I, RICHARD KNIGHT, a citizen of the United States, and resident of Middletown, in the county of Orange and State of New York, have invented certain new and useful Improvements in Target Devices, of which the following is a specification, reference being had therein to the accompanying drawing.

10 My invention relates to miniature target holders and particularly to one adapted to explode a percussion "cap" of fulminating explosive upon the striking the bull's-eye of a recording target.

15 In the drawings, Figure 1 is a front view of my device supported by a sword bayonet.

Fig. 2 is a plan, the bayonet being in section.

20 Fig. 3 is a central front-to-rear vertical section.

Fig. 4 is a section on the line 4—4 of Fig. 2.

25 In these drawings, 11 represents a miniature target slip having an upper aiming target 12 and a lower recording target 13. This target is carried in a block of yieldable material 14, preferably rubber, having target guiding flanges 15, and at 16 a transverse perforation to admit one end of a 30 spring pressed reciprocating pin 17.

The block 14 is carried by a sheet metal frame 18, having block retaining lugs 19, and a supporting stop 20 stamped out of the front portion of the frame 18. The frame 35 18 is bent at 21 to form a rearwardly extending base 22, from which is cut and bent upwardly until vertical, a lug 23 which forms one bearing and serves as a stop for the pin 17. At 24 the frame is also bent upwardly until vertical to form a back 25 for the device.

30 The pin 17 is held in position by bearings, in the lug 23 and the face of the frame 18, which are horizontally aligned with the perforation 16 in the block 14, and this pin has an enlarged head 26 serving the double purpose of a stop and of affording a striking face. A coiled compression spring 27 bears against the lug 23 and a transverse stop 28 carried by the pin 17.

Attached to the back 25 are downwardly extending resilient strips 29 adapted to engage a strip of percussion caps 30, of the usual commercial type. To form a support

for the strip 30, lugs 31 are forced out from the back 25.

In order that the device may be securely supported at any desired elevation, a U-shaped clamp 32 with terminal enlargements 33, is mounted to slide in two holes in the back 25, its branches being provided with coiled compression springs 34, normally holding the connecting portion of the U against the rear face of the back 25. For hanging the device indoors, a hole 36 in the block 25 is provided as an auxiliary means of attachment to a wall or other support.

In use, with a bayonet blade 35 as a support, Figs. 1 and 2 show the clamp 32 holding with sufficient friction to overcome motion due to gravity but yielding to upward or downward pressure for adjusting the height, after the point of the bayonet has been forced into the ground until firm.

35 A rifle equipped with a target practice rod is next brought within striking distance of the target, careful aim taken at the upper target 12, and the trigger released when the sights are alined with the target. If the piece is correctly aimed the practice rod should strike the center of the target 13, which in yielding will permit the practice rod to deliver a hammer-like blow to the pin 17. Said pin will in turn strike a percussion cap of the strip 30 against the back 25, causing an explosion which will leave no doubt as to the correctness of aim.

40 After one cap is exploded, the strip 30 is drawn laterally until an adjacent cap is brought into line with the pin 17, and I prefer to locate the strips 29 so as to bring one cap into line with the pin 17 as one of the following caps comes into contact with one of the strips 29.

45 Obviously, various modifications are possible, and I wish to claim the invention without limitations other than such as appear in allowable claims.

What I claim is:

1. The combination with a backing adapted to support a yielding recording miniature target and provided with a perforation in position to register with the bull's-eye of such target when in place, of an audible signal device, and means terminating at said perforation and actuated only by a hit at the bull's-eye to operate said device.

2. The combination with a holder having

a yielding face adapted to receive a miniature target for recording each impact upon its face, and cap-exploding devices arranged to be operated only by impact at the bull's-eye.

3. The combination with a support for a miniature target, adapted to record each impact of practice devices upon the target face, of a detonating body held in the rear of the bull's-eye, and means for transmitting the force of record making impact at the bull's-eye only to said detonating body.

4. The combination with a miniature yielding, recording target, of a cushioning backing for the same perforated at the bull's-eye point, a holder for the target and backing, a spring returned pin arranged to slide rearwardly from the bull's-eye, and means for holding an explosive cap in the rearward path of said pin.

5. The combination with a miniature target, a cushioning back therefor, and a holder for the back and target, of a frictionally acting clamp carried by the holder and adapted to conform to and firmly engage a support of wedge-like cross section.

6. The combination with a target holder having in front a yielding backing for a

miniature target and in the rear a member for attaching the holder to any suitable support, of means for supporting a cap strip upon said member with its line of caps in the plane of the bull's-eye, a spring arranged for yieldingly resisting the further advance of one of the caps when a preceding one reaches the bull's-eye, a sliding rod extending rearwardly from the bull's-eye toward the aligned cap, and a spring resisting rearward motion of the rod.

7. The combination with a target holder having a yielding backing for a miniature target and a supporting plate at some distance in the rear of the backing, of a spring clamp adapted to hold said plate frictionally against both the thick and thin margins of a service bayonet in vertical position.

8. The combination with a holder for a miniature target adapted to record any impact thereon of a suitable marking device, of a detonating body incapable of materially injuring the record and adapted to be exploded only when a hit is at the bull's-eye.

In testimony whereof I hereunto affix my signature,

RICHARD KNIGHT.
